Primary Examiner—Nanda Bondade*Attorney, Agent, or Firm*—Foley & Lardner; Bernard L. Kleinke[57] **CLAIM**

The ornamental design for a wireless communication device for headsets, as shown and described.

DESCRIPTION

FIG. 1 is a pictorial view of a wireless communication device for headsets illustrating the bottom, right and front sides thereof;

FIG. 2 is a plan view of the top side of the wireless communication device for headsets of FIG. 1;

FIG. 3 is an elevational view of the front side of the wireless communication device for headsets of FIG. 1;

FIG. 4 is an elevational view of the right side of the wireless communication device for headsets of FIG. 1;

FIG. 5 is an elevational view of the left side of the wireless communication device for headsets of FIG. 1;

FIG. 6 is an elevational view of the rear side of the wireless communication device for headsets of FIG. 1;

FIG. 7 is a plan view of the bottom side of the wireless communication device for headsets of FIG. 1;

FIG. 8 is a face view of the wireless communication device for headsets taken along the lines 8—8 of FIG. 3; and,

FIG. 9 is a face view of the wireless communication device for headsets taken along the lines of 9—9 of FIG. 3.

The broken line showing on FIG. 1 is for illustrative purposes only and forms no part of the claimed design.
